Claims priority, application France Feb. 26, 1960

3 Claims. (Cl. 239—464)

The present invention relates to an injector of liquid of the variable-section type, wherein the ratio of the flow rates is high when compared with the ratio of the pressures of the liquid to be injected.

Such injectors are particularly adapted to supply modern air propulsion devices such as turbojets, ramjets, etc., capable of being used between wide altitude and functional limits. They are generally constructed by varying the flow rate of the fuel as a function of its injection pressure.

Previously known injectors of this kind are either of a type comprising movable parts, giving rise to mechanical friction, or of a membrane type. Neither of these types exhibits all of the features necessary, both with respect to accuracy of flow and quality of the spray achieved.

In injectors comprising movable parts, mechanical friction excludes the possibility of ensuring the ability to reproduce operational characteristics so that it is necessary to have individual flow regulating means associated therewith. The provision of such means is a heavy handicap when using several injectors whose individual flow rates must be identical (as is the case for turbojet chambers). It cannot be used for supplying ramjets in which the number of injectors is high.

In deformable-membrane injectors, the rotation of the liquid to be injected, necessary for obtaining a satisfactory spray, is not imparted under good conditions due to the lamination of the liquid at the level of the membrane. Moreover, the angular distribution of the jet is not satisfactory as the membrane has a preferential direction of deformation which is a function of the direction of lamination of the metal.

The object of the present invention is to provide an injector having a high ratio of flow rates and wherein the aforesaid drawbacks are overcome.

The high flow rate ratio injector in accordance with the invention is of a type comprising an injector body with a constant section ejection orifice, a mobile arrangement being frictionlessly movable in the injector body to vary the cross-sectional area of the inlet to said port, said mobile arrangement including a needle-valve having a frusto-conical extremity whose side wall has helicoidal grooves formed therein.

It is essentially characterised in that the mobile arrangement is limited to a needle-valve connected to the injector body through a resilient capsule secured to one extremity of a regulating rod capable of being screwed to a greater or lesser extent into the body of the injector, said resilient capsule being the sole member which both controls the travel of the needle-valve as a function of the pressure of the liquid to be injected, and connects the needle-valve with the injector body.

In one preferred embodiment of the invention, the resilient capsule is an aneroid capsule and each of its two main faces bears a cup in which is housed a swivel, one of these swivels being connected with the needle-valve, the other constituting one of the extremities of the reg-

2

ulating rod. The head of the regulating rod projects outwards from the body of the injector, thereby enabling the needle-valve to be adjusted without dismantling the injector. This adjustment can accordingly be effected on the bench while the injector discharges liquid.

Further features and advantages of the invention, particularly its simplicity of construction, will become apparent from the following description of one preferred embodiment thereof, with reference to the accompanying drawing, the single figure of which illustrates it in section along its axis.

As can be seen in this figure, the injector is comprised by an attachment block 1 screwed to the extremity of a fuel supply tube, an injector body 2 and a mobile ar-

angement.

The attachment block 1 comprises an inlet port 3 for liquid and a nut 4 for the regulating rod 5 of the mobile arrangement. This nut 4 is set into the block 1. It has side faces pierced by holes 6 whose inlets are protected by a filter 7. The said regulating rod is adapted to screw into said nut.

A needle-valve seating 8 and an ejector nozzle 9 are secured, such as by insetting, in the extremity of the body 2. The ejector nozzle 9 comprises a chamber 10 and an ejector orifice 11.

The attachment block 1 and the body 2 of the injector are screwed together. A joint-seal 12 ensures a tight coupling.

The mobile arrangement is composed of a needle-valve 13 supported by the regulating rod 5 through an aneroid capsule 14.

The needle-valve 13 is of the type comprising a cylindrical part and a frusto-conical part, and its side walls have helicoidal grooves 15 formed therein. The outer profile of its conical part is complementary to that of the valve seating 8. Except when the needle-valve 13 is seated on its seating 8, there is no contact or connection of any kind between the mobile arrangement and the body of the injector.

The aneroid capsule 14 is cylindrical. It carries on its main faces cups 16 and 17, having respectively housed therein a swivel 18, attached to the needle-valve 13, and a swivel 19 constituting one extremity of the regulating rod 5. Each of these swivels is held in its respective cup by a circlip 20.

One extremity of the regulating rod 5 projects outside the injector, and after adjustment of the needle-valve it is locked in position by means of a cotter-pin 21.

The operation of the high flow rate ratio injector, forming the subject-matter of the present invention, is as follows:

The liquid enters the injector through port 3, flows through the holes 6 after having passed through the filter 7, enters the capsule chamber 22 and flows into the helicoidal grooves 15 of the needle-valve 13 where it is rotated before reaching the chamber 10 of the ejector nozzle 9.

In this chamber 10, the rotation is accelerated due to the conical configuration of the ejector nozzle 9, and the liquid, after having flowed through the ejector orifice 11, is expelled to the outside of the injector where it atomizes.

The adjustment of the injector is carried out in such a way that when the liquid is either under a pressure which can be arbitrarily selected, or not under pressure at all, the needle-valve remains seated in its seating. In this position the cross-sectional area of the passage for the liquid is fixed by the difference existing between the diameter of the top of the seating and the diameter at the bottom of the helicoidal grooves 15. When the liquid pressure rises upstream of this section, the capsule 14 compresses and lifts the needle-valve 13, thereby increas-

ing the cross-sectional area of the passage for the liquid between the seating and the needle-valve.

Mechanical friction in connection with the needle-valve 13, which is the only guided movable member, is non-existent since this valve is self-centered by the dynamic action of the streams of fluid flowing in the helicoidal grooves, both in the cylindrical and in the conical parts. This self-centering action, which is moreover facilitated by the cylindrical shape of capsule 14, is thus achieved hydraulically without contact by mechanical parts.

Finally, this self-centering is ensured due to the lack of mechanical stress on the needle-valve 13, the connection with other parts being quite free because of the presence of the two swivels 18 and 19 permitting an articulated interconnection.

Lastly, spraying is ensured under the most favourable conditions by maintaining the liquid in rotation in the region between the seating and the needle-valve, then by the reduced dimensions of the chamber 10 of the ejector nozzle 9 thereby reducing losses due to hydraulic friction.

Moreover, the control device for varying the flow rate makes it possible to have a high value for the ratio of the cross-sections. The maximum cross-section is a function of the range of displacement of capsule 14 and also of the angle of the cone between the needle-valve 13 and its seating. By adroit selection between these different variables it is possible to design injectors adapted to extremely varied levels of flow and pressure as well as their ratios.

It is to be understood that the present invention has just been described and illustrated merely by way of explanation without any intention of limiting the same, and that various modifications of detail can be made therein without exceeding its scope.

I claim:

1. Injector having a high flow rate ratio, comprising an attachment block provided with a port for the entry of fuel, said block being screwed to the extremity of a fuel

supply tube, an injector body, said body being screwed on to said attachment block, a needle-valve seating and an ejector nozzle, said seating being in contact with said body and said nozzle, the unit comprising said seating and said nozzle being fixed with respect to said body, a nut with pierced side faces for the passage therethrough of fuel, said nut being attached to said block, a regulating rod, adapted to be screwed into said nut and whose head projects outside the injector, a needle-valve having a cylindrical portion and a frustoconical portion, the outer surface of said needle-valve comprising helicoidal grooves, said frustoconical portion being capable of coming to bear exactly onto said seating, whereas said cylindrical portion does not engage the body of the injector, a resilient member interposed between the regulating rod and the needle-valve, and secured by suitable means to said rod and to said needle-valve, said suitable means being of the type allowing a certain degree of freedom, the displacements of said needle-valve relative to its seating being automatically regulated by the pressure exerted by the fuel on said resilient member, and said needle-valve being applied against its seating for minimum feed.

2. Injector having a high flow rate ratio as defined in claim 1, wherein the resilient member is an aneroid capsule.

3. Injector having a high flow rate ratio as defined in claim 2, wherein the two main faces of the aneroid capsule each have attached thereto a cup in which is housed a swivel, one of these swivels being attached to the adjusting rod and the other to the needle-valve.
